CLAIM

The ornamental design for a projectile loader, as shown and described.

DESCRIPTION

FIG. 1 is a rear perspective view of a projectile loader in accordance with my new design;

FIG. 2 is a front perspective view of the projectile loader as shown in FIG. 1;

FIG. 3 is top plan view of the projectile loader as shown in FIG. 1;

FIG. 4 is a bottom plan view of the projectile loader as shown in FIG. 1;

FIG. 5 is a right elevational view of the projectile loader shown in FIG. 1;

FIG. 6 is a left elevational view of the projectile loader shown in FIG. 1;

FIG. 7 is a front elevational view of the projectile loader shown in FIG. 1; and,

FIG. 8 is a rear elevational view of the projectile loader shown in FIG. 1.

The broken lines shown in the drawings depict portions of the projectile loader that form no part of the claimed design.
